UNITED STATES PATENT OFFICE.

FREDERICK STROBEL, OF MARION, OHIO.

CLOVER-HULLER.

SPECIFICATION forming part of Letters Patent No. 303,330, dated November 18, 1884.

Application filed May 15, 1884. (No model.)

To all whom it may concern:

Be it known that I, FREDERICK STROBEL, a citizen of the United States, and a resident of Marion, in the county of Marion and State 5 of Ohio, have invented certain new and useful Improvements in Clover-Hullers; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a longitudinal vertical sectional 15 view of my improved clover-huller; and Fig. 2 is a top or plan view of the same, showing parts of the frame or outer casing broken away, the better to illustrate the construction of the various parts.

20 Similar letters of reference indicate corresponding parts in both the figures.

My invention consists in the improved construction and combination of parts of a clover-hulling machine, as will be hereinafter more 25 fully described, and particularly pointed out in the claims.

In the accompanying drawings, A represents the frame or outer casing of my improved machine. This frame or casing is provided 30 at its upper and forward end with an inclined feed-board or table, down which the clover-heads are fed so as to pass beneath the thrashing-cylinder B and over the beater C, both of which are of ordinary construction.

35 In the upper portion of the frame A, immediately behind the beater C, are supported the racks D E, the upper rack, D, the spaces between the slats of which are greater than those of the lower rack, E, being placed at 40 such a height as to receive the coarse material thrown from the cylinder B and beater C. These two racks are both supported upon the double cranks F' of the three shafts, F F F', the central shaft being provided at one end with

45 a band-wheel, G, to which the power is applied by means of an endless belt from any suitable source of power, while the opposite end of the shaft and the corresponding ends of the two end shafts are each provided with a small 50 wheel, G', having a wrist-pin, F'', for the attachment of a pitman, G'', the said wrist-pins

being placed at such a distance from the center of the wheels G' that the revolutions of the band-wheel G will reciprocate the two racks in the position shown in dotted lines in Fig. 55 1 of the drawings.

It will be seen that when the clover-heads, after passing beneath the cylinder B and over the beater C, are thrown upon the upper rack, the coarse refuse material will be worked back 60 and out by the said rack, while the seed and finer material will be sifted through the interstices of the upper rack down upon the closer lower rack, E, when the seed are again sifted from the refuse matter, which latter is fed 65 rearwardly and out at the back of the machine, while the seed falls through the interstices of the finer rack E upon a solid bottom, H, extending from the rear part of the frame A to a point immediately over the hulling-70 cylinder I, this solid bottom being placed at such a distance below the lower rack, E, that the said rack will at each of its downward reciprocating motions, feed the seed down the bottom H, which is slightly inclined, into the 75 hulling-cylinder I. The seeds and rubbish are thrown out of the hulling-cylinder upon the bottom M, and are sifted upon the perforated portion O of the same, the seed and finer 80 rubbish or refuse matter falling through upon the riddles N N, where, by aid of the blast from the fan P, the seeds are thoroughly cleaned from the chaff and drop through upon the bottom R, which works the seed rearward to the opening immediately in front of the blast-board P', which opens upon an inclined board, 85 T, leading to the delivery-chute U, a screen, S, being secured a little above the board T, and extending across the mouth of the chute U, the seed working through this screen while 90 the refuse matter, still mingled with the seed, will fall over the lower end of the screen upon the ground or floor. The refuse matter falling from the rear end of the bottom M and riddles N N is received in the tailings-spout 95 Y and is carried up by the elevator W to a point near the middle of the machine, directly over the hulling-cylinder, into which it is discharged. That portion of the bottom M which extends above the drum of the fan P is made 100 solid. The lower rack, E, is provided at a point above the hulling-cylinder with an open-

ing, and the forward end of the said rack, which is made solid, is extended beneath the beater C, so as to receive any matter which fails to pass over and above the said beater 5 and then feeds it rearwardly into the hulling-cylinder.

The various shafts may be run by any suitable system of gearing, which I do not deem it necessary to specify, as any desired form 10 may be employed.

From the foregoing description, taken in connection with the accompanying drawings, the construction and operation of my improved hulling-machine for clover will be readily understood without requiring further explanation. It will be seen that by the use of the 15 double racks the separating of the seed from the refuse matter will be most thoroughly accomplished.

Having thus described my invention, I claim 20 and desire to secure by Letters Patent of the United States—

1. As an improvement in clover-hulling machines, the combination, with the thrashing mechanism, the beater, the hulling mechanism, and the solid inclined bottom H, of the 25 double racks D and E, supported upon and reciprocated by the double-cranked shafts F F, the interstices of the upper rack being 30 larger than those of the lower one, and the lower rack being provided with an opening

immediately over the hulling-cylinder, and having its forward end made solid and extended beneath the beater, whereby any matter passing from the thrashing mechanism and failing to pass over the beater will be caught by the forward solid end of the lower rack and fed down into the hulling-cylinder, as and for the purpose shown and set forth. 35

2. As an improvement in clover-hulling 40 machines, the combination, with the thrashing mechanism, the beater, the hulling mechanism, and the double racks D and E, constructed and operated as described, of the solid inclined bottom H, extending from the 45 rear part of frame A to a point immediately above the hulling-cylinder I, and secured in the frame A at such a distance beneath the lower rack, E, that the seed and light refuse matter falling through the interstices of the 50 said rack upon the said solid bottom will be fed down into the hulling-cylinder by the downward reciprocating movements of the said lower rack, as and for the purpose shown and set forth.

In testimony that I claim the foregoing as my own I have hereunto affixed my signature in presence of two witnesses.

FREDERICK STROBEL.
